COMPRESSOR

Philip A. Friedell and Morley V. Friedell,
Oakland, Calif.

Application May 2, 1939, Serial No. 271,276

8 Claims. (Cl. 230—147)

This invention relates in general to fluid compressors, pumps and motors, and specifically to a combined abutment and discharge valve structure designed to promote maximum mechanical 5 and volumetric efficiency. This invention applies particularly to fluid-actuated and fluid moving devices in which a piston moves through an orbital path about the axis of the cylinder while the piston is maintained against rotation but 10 permitted an oscillating movement about its axis.

This invention is adaptable for use as a compressor for service station, shop and allied uses; as a gas compressor for refrigeration systems, chemical processes, as also for insecticide and 15 paint spraying; as a vacuum pump for use in electric lamp and radio tube manufacture and in chemical and other processes, and in all cases where compression or expansion of gases is to be conducted.

20 The objects and advantages of the invention are as follows:

First; to provide a planetary-type piston with an abutment which coincidentally functions as a discharge valve to insure complete cut-off during 25 the intake period of operation.

Second; to form the discharge port in the cylinder with a minimum area and volume to reduce secondary flash-back to a minimum.

Third; to provide an auxiliary discharge valve 30 for the purpose of restricting the discharge port to minimum volume.

Fourth; to provide an auxiliary discharge valve of maximum lightness and strength and which coincidentally reduces the effective volume of the 35 discharge port.

Other objects and advantages of the invention will become apparent as the following description is read on the drawings forming a part of this specification, and in which similar reference characters are used to designate similar 40 parts throughout the several views, of which:

Fig. 1 is a fragmentary sectional elevation through a compressor showing the invention incorporated therein, and corresponds to a section 45 taken on line 1—1 of Fig. 2.

Fig. 2 is a section taken on line 2—2 of Fig. 1.

Fig. 3 is a fragmentary sectional elevation through the compressor showing a modified form 50 of the invention incorporated therein, and corresponds to a section taken on line 3—3 of Fig. 4.

Fig. 4 is a section taken on line 4—4 of Fig. 3.

Fig. 5 is a top plan view of the abutment.

Fig. 6 is a bottom view of the check-valve stop and valve-chamber plug.

55 Figs. 7 to 10 are diagrammatic views illustrating

the valve action, and in which Fig. 7 shows the piston and abutment at the initial intake and final discharge position; Fig. 8 shows the piston in the position in which the abutment has reached its maximum discharge-port-closing position; Fig. 9 shows the piston and abutment in their intermediate positions with the abutment just ready to start opening the discharge port, and Fig. 10 shows the piston and abutment in the position in which the abutment has reached its maximum discharge-port-opening position.

The usual planetary or oscillating piston type compressor includes a cylinder 10 having heads 11 and 12 in which an eccentric shaft 13 having an eccentric 14 is axially and revolvably mounted, and with a piston 15 operating on the eccentric. A suitable abutment is either pivoted in the cylinder wall, in the piston, or in the heads within the confines of the cylinder, and functions to form a partition between the intake and discharge ports as also to maintain the piston against rotation while permitting an oscillating motion thereof.

This invention utilizes an abutment 16 which has its opposite ends pivoted in the heads 11 and 12 as shown at 17 and 18, and the pivots are illustrated as forming an integral part of the abutment although not restricted to this particular construction.

This abutment is slidable in a slot 19 formed preferably radially in the piston, although it will operate in a chordal slot, and this abutment has an arcuate face 20 which bears in an arcuate seat 21 formed in the inner peripheral wall 22 of the cylinder 10, the arcuate face and seat being formed to a radius having its axis coincident with the axis of the abutment pivot.

The structures so far described are all well known in the art and form a part of the invention only in combination with other structures and modifications described in the following.

The invention resides in the utilization of the abutment as a mechanical discharge valve to prevent all primary flash-back, in combination with the discharge-port chamber of minimum 45 volume to restrict secondary flash-back to an absolute minimum, and an auxiliary valve for the discharge port chamber which valve is of maximum lightness and strength and least resistive to escape of discharge gases, and which valve, due to its specific form further restricts the volume of the discharge port chamber, and it also resides in the sealing means for the abutment and the relieving means for freeing the slot 50 of entrapped oil to prevent hammering.

The sealing means for the abutment consists of a shoe 23 which is slidable in a slot 24 formed in the abutment 16 and having its top face formed to the same radius as that of the bearing face 20 of the abutment. This shoe is urged to cooperate with the bearing seat 21 through the medium of oil supplied under pressure through passages 26 from a passage 27 communicating with a supply 28 of oil under pressure, thus coincidentally thoroughly lubricating the shoe 23 and the seat 21 and forming an effective seal between the discharge side 29 and intake side 30 of the abutment.

The relieving means for freeing the abutment slot 19 of entrapped oil which oil may enter the abutment slot through any clearance between the piston and the cylinder heads or along the front face or high pressure side of the abutment, or which may be fed thereto, as from the oil supply, consists of a bevel 31 formed on the bottom of the abutment to force oil collected in the slot toward and out through the recess 32 formed in the intake-side wall of the abutment, as the abutment approaches the bottom of the slot, the oil thus being forced into the intake side just previous to the beginning of a compression stroke to form a seal across the face of the piston.

The discharge valve, in addition to the abutment, includes a slot 33 formed accurately, and preferably throughout the length of the cylinder and having a circumferential width equal to substantially one half the arcuate travel of the abutment face 20, with one wall of the slot registering with the discharge side of the abutment when the piston is about in its mid-position or terminal of a cycle, as indicated in full lines in Fig. 1, and with the other wall registering with the discharge side of the abutment when the piston has passed its three-quarter position indicated in Fig. 10, or at the discharge end of its arcuate travel as indicated by the dotted line 34 (Fig. 1) thus obtaining maximum opening for discharge of gases with minimum area of discharge passage, and effectively sealing the discharge chamber 45 against return of gas to the cylinder, thus completely obviating any primary flash-back which occurs with the usual types of discharge valves. As is well known, this primary flash-back introduces a loss in both, mechanical and volumetric efficiency, and these losses are completely avoided by this new system.

The discharge port 33 opens directly into a discharge chamber 35 which is formed by a plug 36 which is tapered from both ends toward the center and fitted into a bore 37, and the area of the chamber at the center, measured cross-sectionally of the straight cylindrical portion of the plug, is preferably exactly equal to the area of the discharge port 33, and the cross-sectional area of the chamber and discharge port at any other point is proportionately equal to the relative volume of gas passing that point.

Thus the gas is discharged directly throughout the entire width of the piston and the area of discharge port and chamber at any point is proportionately equal to the relative volume of gas passing that point during discharge, and the discharge chamber is thus maintained at minimum volume.

The discharge chamber opens directly into a check-valve passage 38 which is flared to a relatively large seat 39 for cooperation with a segmento-spherical valve 40, which, due to its hollow spherical form, is unusually strong and light and will seat in any position within its peripheral

limitations, perfectly, and offers the minimum of resistance to the passage of gases when open. This valve also, due to its form, reduces the volume of the passage 38, and it therefore combines the advantages of the disc valve for lightness and of the ball valve for strength and universal seating, without the disadvantages of either.

This valve is limited as to lifting movement by the plug 41 which is formed with depending legs 42 which are slightly spaced from the top of the valve 40, permitting unobstructed passage of the compressed gases to the discharge port 43; the lift of the valve being established to such degree as to form a passage between the valve and its seat equal to the maximum area of the discharge port 33, for maximum efficiency, although there is nothing to prevent increasing the lift if desired.

In the modification illustrated in Figs. 3 and 4, a cylindrical plug 44 is formed with an arcuate slot 45 and is located in the bore 46 with one edge of the slot in registry with the discharge corner 47 of the abutment when the piston is substantially in its mid-position or terminal of a cycle, and the plug is machined in place with the cylinder and forms a part of the abutment seat as indicated at 48.

To prevent possible rotation of this plug, a bore 49 is provided to receive a combined valve seat 30 and sleeve 50 which locks the plug against turning.

The cross-sectional area of the passage 51 formed through sleeve 50, similar to the area of passage 38, is made substantially equal to the area of the discharge port 45 or 33, and a minimum effective volume is produced by limiting the area as measured through the discharge chamber in any plane, to that of the discharge port.

In the diagrammatic views, the operation of the discharge valve is clearly illustrated. In Fig. 7 the piston is on a center in radial alignment with the discharge corner 47 of the abutment and is at its terminal of the discharge movement and this corner is in registry with the leading wall 52 of the discharge slot 33, the piston having completely discharged all compressed gases from the cylinder into the discharge chamber and the abutment has sealed the slot at the very last instant, and the displacement space 53 is filled with a new charge of gas at substantially atmospheric pressure.

As the eccentric shaft rotates in the direction of the arrow 54, the piston moves to a position as shown in Fig. 8, and swings the discharge corner 47 of the abutment to one terminal 55 of its arcuate movement, keeping the passage 33 sealed while the gas in the displacement space 53 is being compressed as indicated by opposed arrows 56, and at the same time a new charge of gas at atmospheric pressure is being admitted to the space 57.

From this point the piston moves to the position shown in Fig. 9 to a center 58 which is located at a point where the discharge corner 47 has again come into registry with the leading side of slot 33.

At this point in the cycle the gas in space 57 is at atmospheric pressure and that in space 53 has been compressed to about one atmosphere, 70 gauge.

The following slight movement of the piston moves the abutment to slightly crack the valve and the gas entrapped within the discharge chamber between the abutment and the check 75

valve 40, if it is of higher pressure than that in the space 53, escapes into this space 53 and forms the secondary flash-back, but being of minimum volume, has little effect on the mechanical efficiency and none whatever on the volumetric efficiency of the compressor, since this entrapped gas cannot escape back to the new intake charge of gas.

Further movement of the piston to a position just ahead of the three-quarter position indicated in Fig. 10, opens the valve fully, and in this position of the piston, the discharge corner 47 of the abutment has reached the other terminal of its arcuate movement and is in registry with the follow side 59 of the discharge slot; the majority of the compressed gas in space 53 has been discharged through the passage and past the check valve 40, except in case of compressing to very high pressures, and the intake space 51 is filled with new gas at atmospheric pressure.

As the piston moves to complete its cycle, the abutment is moved to close the discharge slot, and the final closing movement is very rapid; the valve being fully closed when the piston cooperates with the point located on the cylinder wall at the discharge edge of the abutment, thus completely discharging all compressed gas from the cylinder and sealing the discharge port as shown in Fig. 7, thus entirely obviating primary flashback to the intake.

As a vacuum pump, the operation is the same, except that the intake charge is below atmospheric pressure and is driven out through the discharge, and since there is practically no resistance to overcome, and since the discharge is thoroughly sealed against primary flash-back, vacuum-pumping efficiency is very high.

As will be understood, any primary flash-back escapes into the entire displacement space and reduces the volume of new gas taken in, as this flash-back has direct communication with the intake port 60, thus reducing the volumetric efficiency; since there can be no primary flash-back in this compressor, there can be no reduction in volumetric efficiency which approximates 100%.

It will be understood that variations in construction and arrangement of parts, which variations are consistent with the appended claims, may be resorted to without detracting from the spirit or scope of the invention, or sacrificing any of the advantages thereof.

We claim:

1. An oscillating compressor comprising a cylinder having heads and provided with an articulated abutment seat with the axis of the seat located within the confines of the cylinder, and an abutment pivotally mounted within the interior confines of said cylinder and seating in said seat and a piston slidably cooperating with said abutment; an inlet port for said cylinder; a discharge port formed in the cylinder wall within the confines of said seat and closed by said abutment at the point of final discharge of gas and during the first portion of a cycle of piston operation and opened during the remainder of a cycle, obviating primary flash-back following discharge of gas from the cylinder; said discharge passage having minimum necessary volume communicating with said chamber and a segmento-spherical valve for said passage and means for limiting the lift of said valve; said port having its leading wall aligning with the discharge side of said abutment when said piston is in its final discharge position and thereby completely obviating primary flash-back of gas to the cylinder; said valve having universal seating characteristics and functioning by its spherical undersurface projecting into the discharge passage to restrict the volume of said chamber to reduce secondary flash-back to a minimum.

70 gas from the compressor; and a discharge passage and a checkvalve therefor for said discharge port restricting secondary flash-back to a minimum; said discharge port having parallel walls for creation of minimum volume of discharge passage and being formed throughout the length of said cylinder and having a circumferential width measured on said seat equal to substantially one-half of the arcuate movement of said

4. In a structure as defined in claim 3; said abutment having its intake side formed with a relief intermediate its length and extending throughout the major portion of the length thereof and having its undersurface beveled in the direction of said relief to assist in the discharge of oil from said slot into the intake side of said compressor between the piston and cylinder walls for oil sealing the operating clearance 75

between the piston and the cylinder and to eliminate hammering of the abutment on the bottom of the slot through an entrapped body of oil.

5. In a compressor having a cylinder having a wall with an arcuate seat formed in the inner surface of the wall and an abutment seated in said seat and a discharge port opening into said seat and controlled by said abutment, a discharge chamber having a valve seat and a valve therefor; said chamber having a maximum cross-sectional area at one point only equal to the area of said port with the cross-sectional area decreasing from said point in accordance with the proportionate volume of gas passing during discharge, to substantially zero area at the end of the cylinder, whereby the volume of gas available for secondary flashback or re-expansion is reduced to an absolute minimum.

6. A structure as defined in claim 5 in which said chamber comprises a bore extending through the length of the cylinder wall with one side of the bore opening into said port close to said seat and with a tapered member mounted in said bore and decreasing the cross-sectional area of said bore gradually from that of the area of the port to substantially zero area.

7. In a gas pump cylinder having an intake and an arcuate abutment seat and a discharge port opening through said seat, an abutment seating in said seat and mounted in such manner

as to be capable of moving to alternately uncover and cover said discharge port and a piston operating in said cylinder and cooperating with said abutment to cause said abutment to alternately uncover and cover said discharge port; a bore formed in the wall of the cylinder parallel to the axis of said abutment seat and opening into said discharge port close to the opening of the port through the seat; a check valve for said bore; and a tapered member mounted in said bore and gradually reducing the cross-sectional area of the bore from that of the discharge port to substantially zero between its ends, whereby upon discharge of gases by said piston from said cylinder past said check valve, a minimum volume of gas is retained between the valve and the abutment for re-expansion in said cylinder when said abutment uncovers said port for discharge of another volume of compressed gas from said cylinder.

8. In an oscillatory compressor having a cylinder wall provided with an arcuate abutment seat and an abutment seating therein and a discharge port opening through said seat and controlled by said abutment; a bore formed through the length of said cylinder parallel with and communicating with said port and having a check valve and fitted with a conical plug to reduce the volume of gas for re-expansion.

PHILIP A. FRIEDELL.

MORLEY V. FRIEDELL. 30
